UNITED STATES PATENT OFFICE.

JAMES HENRY TOLSON, OF CLAREMORE, OKLAHOMA.

CELLAR-DOOR.

1,033,214.

Specification of Letters Patent. Patented July 23, 1912.

Application filed September 25, 1911. Serial No. 651,266.

To all whom it may concern:

Be it known that I, JAMES HENRY TOLSON, a citizen of the United States, residing at Claremore, in the county of Rogers and State of Oklahoma, have invented certain new and useful Improvements in Cellar-Doors, of which the following is a specification.

This invention relates to improvements in cellar doors, and has for its particular object to provide a device of that character which will be absolutely water tight or non-leakable.

A further object is to provide a door which automatically locks when in a closed position.

With the above and other objects in view, the present invention consists in the combination and arrangement of the parts as will be hereinafter more fully described, shown in the accompanying drawing, and particularly pointed out in the appended claims, it being understood that changes in the form, proportion, size and minor details may be made within the scope of the claims without departing from the spirit or sacrificing any of the advantages of the invention.

In the accompanying drawing: Figure 1 is a perspective view of my improved door, and Fig. 2 is a vertical longitudinal section taken on the meeting line of the doors showing the edge of one of said doors in elevation.

Like numerals of reference designate corresponding parts in all of the figures of the drawing.

The herein described improved construction is especially adapted to that class of cellar-doors which are mounted upon a frame or base and positioned at an inclination relative to the ground or pavement, but it will be understood that the same will operate to an advantage on horizontally positioned doors.

In the preferred form shown, a rectangular base 3 is provided which surrounds the opening of the pit or cellar, and whose top surface is inclined downwardly from the wall of the building to its front side, and having mounted thereon a pair of doors 4 and 5 which are adapted for bodily sliding and pivotal movements. Said doors 4 and 5 are hinged at their outer edges to rods 6, supported in suitable bearings 7 secured to

the sides of the base, said bearings being spaced apart a predetermined distance at the ends of the rods to form stops for the leaves 8 of the hinges that are secured to the edges of the doors and adapted to slidably engage the rods 6 between said bearings.

Secured to the base and the wall and adapted to project over the upper ends of the doors and under which said upper ends are adapted to slide, is a water-shed 9, which is provided centrally with a recess 10, to accommodate the cleat or weather strip 11, which is secured to the edge of the door 4 and overlaps the door 5, and is provided with a depending lug 12 for a purpose hereinafter described. The base is recessed on both sides, as shown at 13, in which is loosely placed the rollers 14 upon which the doors are supported and moved back and forth.

To prevent the doors from sliding from beneath the water-shed, they are provided on their undersides with stops 15, which are adapted to engage the spring pawls 16, and thereby hold the doors beneath the water-shed. As thus constructed it will be observed that by removing the pawls 16 from engagement with the stops 15, the doors will automatically slide by gravity from beneath the water-shed and can be swung open upon their hinges, and when closed and forced upwardly the spring catches comprising the pawls 16 and the stops 15, will automatically lock the doors in a protected position. Thus is provided a non-leakable cellar-door.

In certain instances where heavy doors are required, means have been provided for sliding said doors beneath the water-shed, and consists of a lever 17, provided with a slot 18, into which is adapted to engage the end of a sliding bolt 19 mounted upon the door 4. Thus when the doors are in their lowermost position, as shown by dotted lines in Fig. 2, the lever is lifted from the position shown in Fig. 1 to the position shown at 20 in Fig. 2, or in alignment with the bolt 19, and the bolt shifted into engagement with the slot 18 and the lever forced backward to the position shown at 21 in Fig. 2, when the doors will be automatically locked as above described. After the doors have been slid into the closed position, the bolt 19 is released from the lever and the lever thrown back to normal position. A lifting

lever for one side is all that is necessary, as the depending lug 12 on one door engages the other door and closes it at the same time.

Having thus fully described the invention, 5 what is claimed is:—

1. A device of the character described, comprising a base provided with recesses and rollers loosely placed in said recesses, a water-shed secured to one end of said base, 10 hinges secured to said base and a door adapted to slide on said hinges and rollers.

2. A device of the character described,

comprising a base, a water-shed secured to one end of said base, hinges secured to said base, a door adapted to slide on said hinges, 15 a lever pivoted to said base, and a bolt mounted on said door and adapted to be thrown into engagement with said lever.

In testimony whereof I affix my signature in presence of two witnesses.

JAMES HENRY TOLSON.

Witnesses:

FRED. W. DODSON,
HARVE CHRISTAIN.
